UNITED STATES PATENT OFFICE

138,075

DESIGN FOR A GARMENT HANGER

Edward E. Burr, Chicago, Ill.

Application March 16, 1944, Serial No. 112,916

Term of patent 3½ years

(Cl. D33—8)

To all whom it may concern:

Be it known that I, Edward E. Burr, a citizen of the United States, residing at Chicago, in the county of Cook and State of Illinois, have invented a new, original, and ornamental Design for a Garment Hanger, of which the following is a specification, reference being had to the accompanying drawing, forming a part thereof.

Fig. 1 is a perspective view of the garment hanger, showing my new design; and
Fig. 2 is a top plan view thereof.

I claim:

The ornamental design for a garment hanger, as shown.

EDWARD E. BURR.
